UNITED STATES PATENT OFFICE.

CARL BIERNAT, OF GLASFORD, ILLINOIS, ASSIGNOR OF ONE-FOURTH TO HARRY GRIGGS, OF GLASFORD, ILLINOIS.

RAILWAY-TIE AND RAIL-FASTENER.

1,280,644.

Specification of Letters Patent.

Patented Oct. 8, 1918.

Application filed June 14, 1918. Serial No. 239,928.

To all whom it may concern:

Be it known that I, CARL BIERNAT, a subject of the Emperor of Austria, residing at Glasford, in the county of Peoria and State 5 of Illinois, have invented certain new and useful Improvements in Railway-Ties and Rail-Fasteners, of which the following is a specification.

The primary object of the invention is 10 the provision of a railway tie formed for readily securing a rail in its operative arrangement thereon without the employment of screws or bolts but readily engaging and locking the rail when placed in position 15 upon the tie.

A further object of the invention is the provision of a rail lock for railway ties adapted for receiving a rail and holding the same in position by reason of the weight 20 of the rail, an automatic auxiliary retainer being also provided when desired.

In the drawings:

Figure 1 is a view partly in side elevation and partly in vertical section of a tie formed 25 after the manner of my invention illustrating a rail in transverse section mounted thereon;

Fig. 2 is a side elevation of the same illustrating the manner of positioning or removing 30 the rail;

Fig. 3 is a sectional view taken upon line III—III of Fig. 1; and

Fig. 4 is a vertical transverse sectional view of the same taken upon line IV—IV 35 of Fig. 1.

My invention provides a tie 10 formed of any suitable material such as wood having enlarged ends or blocks 11 provided with grooves or seats 12 longitudinal of the tie.

40 The sides of each block 11 are cut away at 13 centrally of the sides of the seat 12 adapted for the reception of a rail such as 14 within said cutaway portions transversely of the block 11. A clamp 15 having 45 a semi-circular side 16 and an oppositely positioned jaw 17 is pivoted by means of a bolt 18 in each end of the seat 12.

The clamps 15 are normally facing each other and being tilted upwardly upon the 50 bolts 18 they present receiving jaws 17 for the opposite base flanges 19 of the rail 14 as best illustrated in Fig. 2 of the drawing.

Upon forcing the rail downwardly upon the lower side portions 20 of the clamp jaws, the base of the rail seats within the cutaway 55 portions 13 of the block 11 with the upper sides 21 of the clamp jaws overlying the opposite edges of the rail flanges 19, as illustrated in Fig. 1 of the drawing.

The distance between the jaws 17 is such 60 as to readily receive the rail base or flanges 19 when the clamps are upwardly tilted, but to firmly engage and clamp against the opposite edges of the base 19 upon depressing the clamps 15.

An automatic catch 22 is preferably provided for each clamp 15 being slidably positioned in a socket 23 together with an operating spring 24 whereby the downward movement of the clamp 15 permits the inner 70 end of the catch 22 to seat into a keeper socket 25 in the adjacent side of the clamp. A releasing lever 26 is provided for each catch 22 pivoted as at 27 to the outer side of the block 11 so that pressure upon the 75 lever 26 will release the catch 22 and permit the rail 14 to be forcibly elevated against the holding of the clamps 15 and thereby upwardly tilt the said clamps and disengaging the rail. The catch 22 and lever 26 as 80 well as the sockets 25 may be omitted and the weight of the rail 14 is calculated to be sufficient to maintain the rail seated upon the block 11.

What I claim as new is:

A device of the class described comprising 85 a rail having a longitudinal seat in one end thereof, clamps pivoted in the opposite ends of said seat provided with jaws in their inner faces, a railway rail adapted for positioning within the said jaws when the clamps are upwardly tilted and for clamping engagement therewith when positioned between the clamps when the rail and clamps are in their normal depressed positions, the said clamps having keeper sockets 90 in one side thereof, spring pressed catches 95 slidably carried by the tie adapted for seating within the said sockets when the clamps are depressed, and releasing levers for the 100 said catches pivoted to the outer side of the tie.

In testimony whereof I affix my signature.
CARL BIERNAT.
